UNITED STATES PATENT OFFICE.

JOHN HEISSENBERGER, OF NEW YORK, N. Y.

PUNCHING-MACHINE.

SPECIFICATION forming part of Letters Patent No. 703,959, dated July 1, 1902.

Application filed July 30, 1901. Serial No. 70,238. (No model.)

To all whom it may concern:

Be it known that I, JOHN HEISSENBERGER, a citizen of the United States, and a resident of the city of New York, borough of the Bronx, in the county and State of New York, have invented a new and Improved Punching-Machine, of which the following is a full, clear, and exact description.

The purpose of the invention is to provide a coin-controlled punching-machine of simple and durable construction and which will accurately indicate in pounds upon a dial the force of a blow struck and to so construct the machine that after the blow is delivered the pointer on the dial will remain in position to indicate the record made until said pointer is purposely released to be restored to its normal position at zero.

Another purpose of the invention is to provide a construction whereby the punching-bag may be struck in the absence of a coin being deposited without having any influence upon the dial or other parts of the machine.

A further purpose of the invention is to provide a positively-acting yet simple locking mechanism for the dial-shaft and a readily-operated device for breaking the locking connection at the dial-shaft.

The invention consists in the novel construction and combination of the several parts, as will be hereinafter fully set forth, and pointed out in the claim.

Reference is to be had to the accompanying drawings, forming a part of this specification, in which similar characters of reference indicate corresponding parts in all the figures.

Figure 1 is a front elevation of the machine. Fig. 2 is a side elevation, parts being broken away. Fig. 3 is a vertical section through the pocket portion of the machine, illustrating parts in section and parts in elevation, coöperating with the pocket mechanism. Fig. 4 is a horizontal section taken practically on the line 4-4 of Fig. 3. Fig. 5 is a vertical section through the machine, taken at a point near its center; and Fig. 6 is a vertical section taken at the rear of the machine at right angles to the section shown in Fig. 5.

A represents the casing of the machine, which may be of any desired shape, and this casing, preferably at its front upper portion,

is provided with a dial B, upon which a scale in pounds and fractions of a pound is produced. At the lower portion of the casing A an outwardly-extending sleeve 10 is formed at the front, and in this sleeve the collar 11 of a punching-pad C is adapted to slide, as is likewise a portion of the pad proper. This collar 11 is preferably made solid at the back and is therefore more in the nature of a cup-face, and at the center of the said collar or cup face a horizontal shaft 12 is secured at one of its ends, which shaft slides loosely through an opening in the front of the casing A at the center of the collar 10, secured to the casing, as is shown in Fig. 5. The rear end of the shaft 12 is adapted to slide freely in a fixed horizontal sleeve 13, located within the case or casing, as is also shown in Fig. 5.

A trip-finger 14 is secured on the shaft 12, extending above and below it, this finger being located at the forward portion of the shaft, yet within the case or casing A, as is shown in Figs. 2, 3, and 5. This finger 14 is preferably attached to the shaft in a removable manner and is provided with a washer 14^a at its outer face, which washer surrounds the shaft 12. In the normal position of the shaft the striking-pad C bears against the inner face of the casing A. An offset 15 is located on the shaft 12 at the inner face of the trip-finger 14, and a spring 16 is coiled around the said shaft, bearing against the said offset and against the rear of the casing A, the said spring being likewise coiled around the fixed sleeve 13, as is shown in Fig. 5.

The lower member of the finger 14 has movement between the members of a bifurcated horizontal guide 17, and the upper member of the finger 14 has movement between the members of a shorter bifurcated horizontal guide 18, both guides 17 and 18 being secured to the front face of the said casing at the front inner face of said casing. The casing A may be braced by any number of bolts 19, and the space 20 below the shaft 12 constitutes a receptacle adapted to receive the coins deposited in the casing. As stated, the casing A may be of any form and is usually supported upon a pedestal 21 of any type.

The pointer 23 of the dial B is attached to a shaft 24, journaled in the front upper por-

tion of the casing A at one end and in the pendent portion of a bracket 25 at the opposite end, or an equivalent support for the inner end of the said shaft 24 may be provided. 5 This shaft is preferably provided with an attached sleeve 26 within the casing A near the outer end of the said shaft, and the inner end of a cord or chain 27 is attached to this sleeve or to the shaft and is given one or more coils 10 around said sleeve. The cord or chain 27 is carried downward within the casing in direction of the front and over a guide-pulley 28, supported in bearings at the front inner portion of the casing, the lower end of the said 15 cord or chain 27 being attached to a screw 29, adjustably secured in an offset 29^a from a foot 30 at the bottom portion of a lever 31. This lever 31 extends upward, and, as shown at 32, is fulcrumed near its upper end on a lug carried by the bracket 25. At the upper end of the said lever 31 a spring 33 is attached, the spring being likewise secured to the forward portion of the casing. This spring tends to carry the foot portion of the lever 31 away 20 from the upper member of the trip-finger 14. 25 The foot 30 of the lever 31 is provided with a pocket 34, vertically produced in its forward face, as shown in Fig. 4, in the lower portion of which pocket the inner ends of the upper 30 bifurcated guide 18 enter when the foot is in its normal position, as is shown in Figs. 3 and 4. This foot is likewise provided with a central vertical opening 35, communicating with the pocket 34, so that when the foot 30 is in its 35 normal position and in the absence of a coin a blow is given to the pad C the shaft 12 and finger 14 may move rearward without interfering with the lever 31 or its foot-section. Since the said lever is not brought into action 40 unless a coin 36 is placed in the pocket 34, resting upon the inner face of the upper bifurcated guide 18, as shown in Fig. 3, the coin being then between the forward face of the foot 30 and the inner face of the upper 45 member of the finger 14, so that when a blow is delivered on the pad C and the shaft 12 and finger 14 are carried inward against the tension of the spring 16 the coin serves to close the slot 35, and consequently the foot 50 portion of the lever 31 must move with the shaft 12.

The coin is delivered into the pocket 34 through the medium of a chute 36^a, which is inclined downward from the front face of the 55 casing in direction of the pocket and has communication at its upper portion with a slot 37, produced in the front face of the casing. In order that the coin cannot possibly leave the pocket until the proper time after 60 having once been deposited therein, a shield 38 is carried down from the chute 36^a to an engagement with the upper guide 18, and this shield may likewise be carried forward, below the guide, as is shown in Fig. 4. The 65 coin is released from the pocket in which it is placed when the shaft 12 has been driven far enough inward to carry the foot-section 30 of

the lever 31 some distance from the front of the machine, as shown in Fig. 2, whereupon the coin will fall into the receiving-chamber 70 20, and, through mechanism to be hereinafter described, after the blow has been struck which carries the foot portion of the lever 31 rearward, the said foot portion of the lever remains in its rearward position, while the 75 shaft 12 is restored to its normal position by the spring 16 as soon as the pad C is relieved from the force of the blow. When the foot portion of the lever 31 is thus carried to its rearward position, the shaft 24 is turned and 80 the pointer 23 will indicate on the dial in pounds and fractions thereof the force of the blow delivered. The pointer will remain in its indicating position until released by a mechanism to be hereinafter described. 85

A hard-metal disk 39 is secured upon the pointer-shaft 24, and this hard-metal disk is provided with an upper extension 40, to which extension one end of a cord or chain 41 is attached, which cord or chain passes down at 90 the side of the pointer-shaft 24 opposite that at which the cord or chain 27 passes and which is attached to the foot-section or coin-receiving receptacle of the lever 31. At the lower end of this cord or rope 41 a spring 42 95 is secured, and this spring is likewise attached to a bracket 43, which extends rearwardly from the front inner face of the casing A, as is best shown in Fig. 5. A locking-arm 44 is pivotally attached to the inner end 100 of the bracket 43. This locking-arm extends upward and is provided with a slot 45 at its upper end, which slot receives the inner portion of the shaft 24 back of the disk 39. At the front face of the upper end of the locking-arm 44 a soft-metal disk 46 is secured, having a slot in its upper portion corresponding to the slot 45 for the passage of the pointer-shaft 24. This soft-metal disk 46, which is a locking-disk, is held with more or less friction against the hard-metal disk 39, attached to the pointer-shaft 24, by means of a spring 49, attached to the front inner face of the casing A and to a screw 47, which screw is passed through a suitable opening in the locking-arm 44. The said screw is provided with a thumb-nut 48, which has bearing against the inner face of the said locking-arm 44, as is also best shown in Fig. 5. Under this arrangement it is obvious that the frictional engagement between the soft-metal disk 46, carried by the locking-arm 44, and the disk 39, carried by the pointer-shaft 24, 110 115 may be regulated as desired.

A trip-bar 50 is made to enter the casing A 120 from the front below the dial B, and this trip-bar 50 extends through an opening 51 in the locking-arm 44 and is provided with an extension 52, carried upward and horizontally rearward, the upper inner end 53 of which 125 extension is reduced to form a shoulder, and the reduced portion of the extension 52 is carried through an opening in the locking-arm 44. Thus it will be observed that by press-

ing the trip-bar 50 inward the locking-disk 46 will be carried out of engagement with the disk 39 on the shaft 24.

In the general operation of the machine a coin is introduced into the coin-chute 36 through the slot 37, whereupon the coin will drop into the pocket 34 and will close the opening 35 in the section of the lever 31 in which the said pocket is formed, so that when a blow is received by the pad C and the shaft or plunger 12 is forced inward the upper member of the finger 14 will engage with the coin in the pocket 34 and will carry the foot 30 of the lever 31 rearward through the medium of the cord or chain 27, thus turning the pointer-shaft 24, causing the pointer to indicate on the dial B the force of the blow measured by pounds. The cord or chain 27 in performing this action uncoils from the pointer-shaft 24 and causes the cord or chain 41 at the opposite side of the shaft 24 to coil thereon. The frictional engagement between the locking-disk 46 and the disk 39, carried by the pointer-shaft 24, will cause the lower portion of the lever 31, carrying the coin-receptacle, to be held in a rearward position to which it was carried, thus permitting a person to investigate at leisure the face of the dial. After such investigation has been made the parts of the machine may be restored to their normal position by pushing inward the trip-bar 50, which action carries the locking-disk 46 from the disk 39 on the pointer-shaft and causes the cord or chain 41 to uncoil from the pointer-shaft and restore the pointer to zero on the dial B, while at the same time the spring 33 will act to bring back the foot-section 30 of the lever 31 to an engagement with the upper member of the finger 14, which will now be in its normal position, assisted by the spring 42, and the cord or chain 27 will be again coiled on the pointer-shaft 24 for action

on the said shaft to indicate the force of a blow which may be subsequently given.

It will be understood, as stated, that when the lever 31 is carried rearward the coin is released and drops into the receiving chamber or receptacle 20. It will be further observed that the extension 52 from the trip-bar 50 is carried up quite close to the upper portion of the releasing-arm 44, and therefore but a slight inward movement on the part of the trip-bar 50 is necessary to cause a disconnection between the locking-disk 46 of soft metal and the disk 39, which is attached to the dial-shaft 24.

Having thus described my invention, I claim as new and desire to secure by Letters Patent—

In a punching-machine, the combination, with the casing, a dial, a pointer, and rotary shaft carrying the latter and having a disk 39, of a slidable, spring-pressed, pad-carrying shaft, a pivoted lever, and means for operatively connecting it with the pad-shaft, a rope connecting the pivoted lever with the pointer-carrying shaft, so that the swinging movement of one effects rotation of the other, means for retracting the pointer-carrying shaft, the pivoted lever 44 bearing at its free upper end upon said disk 39, a spring holding the lever in frictional engagement with the disk, and means for varying the pressure, and the slidable trip-bars projecting through the front of the casing and engaging at the inner end the lever 44, all operating as shown and described.

In testimony whereof I have signed my name to this specification in the presence of two subscribing witnesses.

JOHN HEISSENBERGER.
